ART OF DETECTING TRAMP MATERIAL

Robert L. Manegold, Shorewood, and Ira H. Wynne, Milwaukee, Wis., assignors to Dings Magnetic Separator Co., Milwaukee, Wis., a corporation of Wisconsin

Application December 22, 1945, Serial No. 636,870

1 Claim. (Cl. 177—311)

1
Our invention relates generally to improvements in the art of detecting the presence of tramp material in masses of primary material, and relates more particularly to an improved system of locating dangerous chunks of unduly hard substance accidentally deposited in bulk materials which are subject to further treatment in mechanisms unadapted to handle the tramp material without damage.

The principal object of the present invention is to provide an improved method of and instrumentalities for utilizing magnetism to most effectively detect the presence of batches of magnetic or non-magnetic tramp substances, within a mass of any kind of primary material which has previously been handled or treated by equipment from which the tramp batches have broken away or become separated.

In many industries, and especially in the mining industry, masses of primary bulk materials such as rock, coal and ore are initially treated or handled in equipment such as cars, steam shovels, and crushers having brake shoes, bucket teeth, liners, or mantles formed of very hard and relatively uncrushable substance, portions of which known as tramp batches break off or become separated from the equipment and fall into the masses of primary material. When the bulk primary material is subsequently subjected to further treatment such as fine crushing, the tramp batches are liable to cause great damage to the subsequent treating equipment, so that the hard and uncrushable batches should be effectively removed before the primary material is further treated. Such detection and removal of the tramp or foreign material should preferably be effected while the bulk material is advancing or moving from the primary treating equipment toward the secondary or subsequent treating equipment.

Many different methods of and apparatus for effecting detection and removal of these batches of tramp substance, have heretofore been proposed and used quite successfully in connection with certain types of tramp material. When this tramp material is magnetic, and the bulk or primary material is non-magnetic, it is a simple matter to accurately detect the presence of the magnetic tramp batches by merely subjecting them to magnetic influence sufficient to cause the temporarily magnetized batches to create a detecting electric current in a secondary coil associated with sensitive signalling mechanism. This cannot however be done when the tramp batches are composed of non-magnetic material such as

manganese steel which is extensively used in the construction of brake shoes for cars, teeth for shovel buckets, and liners and mantles for crushers. The prior method furthermore cannot be readily utilized when the primary material is composed of more or less magnetic material, such as magnetic ore; and the equipment required in carrying on the prior detection method is also relatively complicated since it requires the provision of a complicated primary energizing coil and magnet, which besides being relatively intricate and of expensive construction, must be constantly electrically energized.

In an effort to obviate the difficulty of detecting the presence of tramp batches of non-magnetic material such as manganese steel, it has heretofore been proposed to insert local plugs of magnetic metal in the portions of the initial handling equipment which were most likely to break away. When one or more of these plugs was present in a tramp batch and was subsequently subjected to temporary magnetic influence, they would serve to detect the presence of their carrying batches by setting up detecting electric currents in the secondary coils of the detector or signalling mechanism; but if no such plugs happen to be present within the tramp batches no detection thereof was possible. With this prior method the plugs which were embedded in the tramp batches were not of a permanently magnetized nature but were only composed of material which could be magnetized when subjected to strong electro-magnetic influence; and we have discovered that by making the plugs of highly magnetic material and by permanently magnetizing the same, the plugs themselves will create the desired detecting currents in the secondary coils of the detecting apparatus, without resorting to the use of the primary electrically energized and complicated coils heretofore used.

It is therefore a more specific object of our present invention to provide a simple but highly effective method of detecting the presence of batches of any kind of undesirable tramp material in a mass of any kind of primary material, regardless of whether the tramp batches or the primary material are composed of magnetic or non-magnetic substance.

Another specific object of this invention is to provide an improved system whereby the presence of undesirable batches of tramp material such as manganese steel chunks, in a moving mass of other material such as ore, rock, or coal, may be quickly and accurately detected and removed before the tramp pieces damage subse-

quent equipment for treating the bulk material.

A further specific object of the invention is to provide simplified apparatus for effectively detecting the presence of tramp pieces of material in a traveling mass of primary material, with the aid of permanently magnetized local cores associated with the tramp material and coacting with a simple detector coil and signal assemblage.

Still another specific object of our invention is to provide an improved method of and apparatus for positively detecting the presence of non-magnetic batches of objectionable material within travelling masses of primary bulk materials of various kinds.

These and other specific objects and advantages of the present improvement will be apparent from the following detailed description.

A clear conception of the features constituting our present invention, and of the method and apparatus involved in commercial exploitation thereof, may be had by referring to the drawing accompanying and forming a part of this specification wherein like reference characters designate the same or similar parts in the various views.

Fig. 1 is a perspective view of a typical shovel or dipper tooth such as is ordinarily used on mechanical bulk material handling dippers or shovel buckets, showing one of our improved permanently magnetized cores embedded therein;

Fig. 2 is a fragmentary part sectional side view of a brake shoe and wheel for a car such as customarily utilized for handling coal and ore withdrawn from a mine, also showing several of our improved permanently magnetized detector cores embedded in the shoe liner;

Fig. 3 is a fragmentary central vertical section through the discharge portion of a typical gyratory crusher, likewise showing several of our improved permanently magnetized local cores embedded in the head mantle and concave liner;

Fig. 4 is a fragmentary vertical section through the outlet of a typical jaw crusher, again showing the improved permanently magnetized detector cores embedded in the discharge ends of the liners for the fixed and movable crushing jaws; and

Fig. 5 is a diagrammatic transverse vertical section through a loaded bulk material belt conveyor having a shovel tooth containing one of the improved permanently magnetized cores embedded in the primary material mass, and showing the action of the magnetized core upon a typical detector coil.

While the disclosure in the drawing has been limited to only a few typical embodiments or uses of the present invention, it is not our desire or intent to unnecessarily restrict the utility of the improved method by virtue of this limited showing.

In accordance with our present improved method of detecting the presence in a mass of any kind of bulk primary material, of chunks or batches of undesirable tramp material which has been accidentally broken or separated from initial equipment by which the primary material has previously been handled or treated, we fixedly associate local permanently magnetized cores with local portions of the equipment which are subject to relatively frequent breakage and release of tramp batches into the primary mass, and we subsequently utilize the inherent or permanent magnetism of the released cores to positively detect the presence of the tramp batches within the mass of primary material. The primary

material may have various characteristics and may be either magnetic or non-magnetic, and the same is true of the tramp material except for the local permanently magnetized cores embedded therein, which are preferably formed of material such as "Alnico" which is susceptible of strong and durable permanent magnetization. These permanently magnetized cores may be embedded within or otherwise rigidly associated with the portions of the initial handling equipment, which are most subject to release of tramp pieces, and the actual detection of the presence and location of the tramp batches is preferably effected while they are travelling embedded in or reposing on a layer or stream of the primary material travelling from the initial equipment toward subsequent treating equipment such as fine crushers or the like.

Referring to the drawing, Fig. 1 illustrates a typical dipper or shovel bucket tooth 8 having a local permanently magnetized cylindrical core 9 of considerable size fixedly embedded therein near its point. These teeth 8 are ordinarily formed of wear-resistant non-magnetic metal such as manganese steel, and rather frequently drop off of their carrier buckets and mingle with the bulk material which is being handled. If permitted to subsequently enter the crushing zones of various types of crushers, these hard teeth 8 may cause considerable damage or stall the crushing machines.

In Fig. 2 is shown a typical brake assemblage for cars such as are customarily utilized to remove coal and ore from mines, the assembly comprising a wheel 10 and a cooperating brake shoe 11, the latter being provided with a wear-resistant liner 12 having a series of permanently magnetized cores 9 fixedly embedded in local portions thereof. The shoe liners 12 may be formed of manganese steel or other hard but non-magnetic material and chunks 13 are rather frequently broken therefrom and become mixed with the bulk coal or other primary material which is being handled by the cars.

Fig. 3 is a typical representation of a gyratory crusher such as used for initially reducing ore, rock, or the like, and this crusher comprises in general a crushing head 14 carried by a gyratory shaft 15 and being protected by a wear-resistant manganese steel mantle 16; and a fixed crushing concave 17 protected by a wear-resistant manganese steel liner 18 which cooperates with the head mantle 16 to provide an intervening crushing chamber 19. The discharge ends of the mantle 16 and liner 18 are preferably provided with fixedly embedded permanently magnetized cores 9 at local places, that is, wherever chunks 13 of these protective elements are apt to break away and fall into the crushed primary material.

In Fig. 4 there is shown a typical jaw crusher such as is frequently utilized to initially break pit or mine run rock or coal, and this crusher consists primarily of a movable jaw 20 protected by a manganese steel or similar wear plate 21, and a fixed jaw 22 likewise protected by a suitable wear plate 23 cooperating with the plate 21 to provide a crushing zone 24. The discharge or outlet portions of the wear plates 21, 23 of this jaw crusher, are likewise provided with fixedly embedded permanently magnetized cores 9 at the local places where chunks 13 are more apt to break off and become mixed with the product, and the plates 21, 23 are usually constructed of non-magnetic hard material such as manganese steel or the like. Now referring specifically to Fig. 5, after the

primary or bulk material 25 has been initially handled with equipment such as a dipper or shovel, or a car, or a coarse crusher, at the source of supply, it is usually transported in a continuous stream or a relatively thin layer, to a subsequent treating machine such as a fine crusher, with the aid of a conveyor belt 26. In order to detect the presence of relatively uncrushable pieces or tramp batches such as a dipper tooth 8 or a chunk 9 of similar material, having one or more permanently magnetized detector cores 9 embedded therein, we provide only a detector coil or solenoid 27 comprising a large number of turns of fine insulated wire wound upon a suitable form of insulated material and having a laminated magnetic core 28 therein, which is located near the path of travel of the conveyor belt 26, preferably with its axis disposed parallel to the said path. This solenoid 27 may be connected to a sensitive signal or indicating device operable by electric current induced in the solenoid by lines of force emanating from a magnetized core 9 which is carried within the range of action of the solenoid windings by the conveyor belt 26, in the usual and well known manner, thus completing the equipment necessary for detection purposes with our improved method.

During normal use of the improved apparatus while carrying on our new method of detecting, the portions of the equipment which are normally subject to breakage and release of portions or tramp batches into the primary material, are provided with permanently magnetized cores of highly magnetic material such as "Alnico" metal, as indicated in Figs. 1 to 4 inclusive. When a chunk or batch 13 of the equipment is thus broken away and is deposited into the primary material 25 as shown in Fig. 5, the permanently magnetized core embedded within the broken away piece will constantly radiate or send out lines of flux in all directions. When no foreign material or tramp batch is contained within the primary material 25 which passes the solenoid 27, this solenoid remains inactive; but when a piece of tramp material such as a tooth 8 containing a permanently magnetized core 9 comes within range of the solenoid 27, the flux lines radiating in all directions from the magnetized core will immediately produce electric currents in the solenoid. The low voltage current thus produced in the solenoid 27 will be transmitted to the signal apparatus and will thus notify the operator that tramp material is contained within the moving mass of material 25 in the locality of the solenoid 27. The operator may then remove the detected tramp material, thus insuring safety in operation for the subsequent equipment in which the material 25 is to be treated. Since the cores 9 are strongly permanently magnetized, the de-

tection will be positive and accurate, and the signalling device will be operated in a manner which will leave little doubt in the mind of the operator.

From the foregoing detailed description it will be apparent that our present invention provides a simple but highly accurate method of detecting tramp batches within a moving mass of primary material 25, even if the tramp batches are composed primarily of non-magnetic material. The 10 strongly permanently magnetized cores 9 will afford positive protection even if the material 25 is magnetic in character, so that it is immaterial whether the mass of primary material is of a magnetic or a non-magnetic nature. It has been 15 found that a relatively small core of permanently magnetized material such as "Alnico" metal, will positively and definitely actuate a solenoid 27 such as heretofore used in conjunction with electrically energized magnets, without necessity of utilizing such complicated magnet structures, thereby vastly simplifying the detecting mechanism, while insuring perfect detection regardless of the magnetic or non-magnetic characteristics of the material 25 and of the tramp batches.

20 It should be understood that it is not desired to limit this invention to the exact steps of the method, or to the precise construction of the apparatus, herein described and shown, for various modifications within the scope of the appended 25 claim may occur to persons skilled in the art.

We claim:

30 The method of detecting in a moving mass of magnetic primary material the presence of non-magnetic batches of tramp material accidentally broken away from equipment which has previously handled the primary material, which method comprises, embedding intensely and permanently magnetized local cores in various portions of the equipment which are subject to breakage 35 and release of non-magnetic tramp batches containing one or more of said cores into the magnetic primary mass, and utilizing the inherent intense magnetization of said released cores to indicate the location of and to facilitate removal 40 of the non-magnetic tramp batches from the mass of magnetic primary material while in motion.
